Primary Examiner — L. A. Grabenstetter(74) *Attorney, Agent, or Firm* — Thomas M. Joseph, Esq(57) **CLAIM**

The ornamental design for a carrying case for mobile phones and credit cards, as shown and described.

DESCRIPTION

FIG. 1 is a perspective view showing my new design;

FIG. 2 is a top plan view thereof;

FIG. 3 is a bottom plan view thereof;

FIG. 4 is a left side view thereof;

FIG. 5 is a right side view thereof;

FIG. 6 is a front view thereof; and,

FIG. 7 is a rear view thereof.

The broken lines shown in FIGS. 1-7 illustrate environmental structure. None of the broken lines form part of the claimed design.

1 Claim, 4 Drawing Sheets(56)
